DESIGN FOR A FOLDING MIRROR OR SIMILAR ARTICLE

David Bezborodko, New York, N. Y.

Application October 29, 1942, Serial No. 108,635

Term of patent 3½ years

To all whom it may concern:

Be it known that I, David Bezborodko, a Russian refugee with Nansen Passport, residing at New York city, in the county of New York and State of New York, have invented a new, original, and ornamental Design for a Folding Mirror or Similar Article, of which the following is a specification, reference being had to the accompanying drawing, forming part thereof.

Figure 1 is a perspective view of a folding mirror or similar article, showing my new design as it appears in open position.

Figure 2 is a top plan view of the article as it appears when laid out flat to full length.

Figure 3 is a side elevational view of the article as it appears in folded position.

I claim:

The ornamental design for a folding mirror or similar article, substantially as shown and described.

DAVID BEZBORODKO.
